Patented Oct. 25, 1966

206,099

COMBINED DISPENSER AND RECEPTACLE

Robert J. Gantner, 2 Henneberry, Golf, Ill.

Filed Mar. 7, 1966, Ser. No. 1,333

Term of patent 14 years

(Cl. D58—17)

FIG. 1 is a perspective view of a combined dispenser and receptacle embodying my new design;

FIG. 2 is an end elevational view thereof;

FIG. 3 is a front elevational view thereof;

FIG. 4 is a rear elevational view thereof;

FIG. 5 is a top plan view thereof; and

FIG. 6 is a bottom plan view thereof.

I claim:

The ornamental design for a combined dispenser and receptacle, substantially as shown.
